UNITED STATES PATENT OFFICE

98,245

DESIGN FOR A CIGARETTE AND CIGAR LIGHTER

Irving Florman, New York, N. Y.

Application September 14, 1935, Serial No. 58,552

Term of patent 14 years

To all whom it may concern:

Be it known that I, Irving Florman, a citizen of the United States, residing at New York, in the county of New York and State of New York, have invented a new, original, and ornamental Design for a Cigarette and Cigar Lighter, of which the following is a specification, reference being had to the accompanying drawing, forming a part thereof.

Fig. 1 is a front elevational view of the cigarette and cigar lighter, showing my new design.

Fig. 2 is a plan view of the top of the same.

Fig. 3 is an enlarged isometric view of my design.

The dominant feature of my design is the milling upon the front upper edge.

I claim:

The ornamental design for a cigarette and cigar lighter as shown and described.

IRVING FLORMAN.
